SLED

Victor H. Czegka, Ipswich, Mass.

Application November 2, 1943, Serial No. 508,675

4 Claims. (Cl. 280—12)

This invention relates to sleds and particularly to sleds designed for use in hauling loads either by hand or by dog team.

One of the objects of the invention is to provide a novel sled which is very sturdy in its construction but which has a relatively light weight.

Other objects of the invention are to improve sleds of this nature in various ways as will be hereinafter set forth.

In the drawings wherein I have illustrated a selected embodiment of my invention,

Fig. 1 is a perspective view of the sled.

Fig. 2 is an enlarged fragmentary side view showing the manner in which the gee pole is attached to the sled.

Fig. 3 is a transverse section through the sled looking toward the front.

Fig. 4 is a fragmentary view showing the manner of attaching the front or rear cross piece to the ends of the runners.

Fig. 5 is a section on the line 5—5, Fig. 4.

Fig. 6 is a perspective view of one of the bridge elements.

The sled is made with the usual runners 2 and 3 which are connected intermediate of their ends by a plurality of bridge elements 4 and are connected at their ends by cross bars 5. Each runner is formed with flat upturned ends 6.

The bridge elements 4 are made of flat stock and are bent to present the horizontal central portion 7 and the downturned legs 8 at the ends. The flat part of each runner 2 and 3 is formed with an upstanding rib 9 provided with recesses in which the ends 10 of the leg portions 8 of the bridge elements are received. These leg portions are secured to the runners by thongs or lacing 71, the leg portions of the bridge elements and the upstanding rib 9 being provided with apertures through which the thongs or lacing can be threaded.

Associated with each leg element is a bunk member 11 which serves to stiffen and reinforce the bridge elements and also serves to provide a support for the outside slats as will be presently described. Each bunk member has the shape shown in dotted lines in Fig. 3 and each bridge element 4 is provided with two slots 13, 14 in which the corresponding bunk member 11 is received. These slots 13 and 14 extend throughout the curved portions 15 of each bridge element which connect the horizontal central portion to the legs 8. Each bunk is formed with the widened end portions 16 which occupy the slots 13 and 14 of the corresponding bridge element and which project slightly beyond the leg portions 8 thereof.

The upper edge 17 of each bunk lies underneath the central horizontal portion 7 of the corresponding bridge element and each bunk is formed with an upstanding shoulder 18 which engages the inner end 19 of the slot 14. The shoulder 18 has a depth equivalent to the thickness of the bridge element 7 and thus the surfaces 20 of each bunk are flush with the top face of the bridge element. The underfaces 21 at the ends of each bunk rest against the lower ends 22 of the slots 13, 14.

Each bunk is assembled with its bridge element by inserting the left hand end through the slot 14 of the bridge element as shown in dotted lines Fig. 3 and then moving the bunk transversely through said slot and entering said left hand end of the bunk through the slot 13. Each bunk is formed with a second upstanding shoulder 23 similar to the shoulder 18 but situated nearer the end of the bunk than said shoulder 18. When the bunk has been assembled with its bridge member with its shoulder 18 in engagement with the end 19 of the slot 14, the shoulder 23 will be separated somewhat from the inner end 24 of the slot 13. A key element 25 is then inserted between the shoulder 23 and the end 24 of the slot 13, thereby locking the bunk in position and when the bunk is thus locked it stiffens and strengthens the bridge element.

30 The deck of the sled is formed by usual slats 26, the central one of which rests on the top surfaces of the bridge members 4, the others of which rest on the surfaces 20 of the bunks, one of the slats covering the keys 25 of the various bridge elements thereby holding said keys in position and another slat overlapping the shoulders 18 of the various bunks and having its inner edge resting on the top surface of the bridge elements.

40 The cross bars 5 at each end of the sled have a sort of triangular cross-sectional shape, each cross member having an inclined underface 27 which rests against the end 6 of the runner and having a horizontal but stepped upper face 45 presenting the lower surface 28 on which the ends of the slats 26 rest and the upper surface 29 flush with the top of the slats, said slats coming against the shoulder 30 between said surfaces 28 and 29.

50 Each cross piece is anchored to the runner by a tie bolt 31 which extends through openings 32 and 33 formed in the runner and cross piece respectively. Each runner has associated therewith a U-shaped metal clip 53 which embraces the runner and through which the bolt 31 passes,

the head of the bolt engaging the outside of the clip. This tie bolt 31 is provided with a clamping nut 34 which is screw-threaded thereto and which is located in a recess 35 formed in the cross bar 5. The apertures 32 and 33 are somewhat larger than the bolt 31 so as to allow for the necessary yielding movement as the sled is drawn over a rough surface.

The sled is provided with a gee pole by which the sled can be guided, and one feature of the invention relates to the manner in which this gee pole is attached to the sled.

The gee pole is indicated at 36 and it is located at one side of the sled. Pivotal secured to the front end of the sled is a pole-supporting bracket 37. This bracket is shown as formed with two side bars 38, 39 which are pivotally connected at 40 and 41 to brackets 42 carried by the front cross bar 5. This pole-supporting bracket 37 carries at its front end a hub 43 in which is mounted an eye bolt 44 provided with an eye or loop 45 through which the gee pole extends. The bracket 37 has an angular arrangement, the leg 38 being shorter than the leg 39 so that the hub 43 stands at one side of the sled and the eye 45 of the eye bolt is outside the vertical plane of the sled runner.

The lower end of the gee pole which is pointed as shown at 46 extends into the eye 47 of another eye bolt 48 that is anchored in the leg 8 of the front bridge member. With this construction the gee pole extends forwardly and outwardly from the adjacent sled runner so that the front end of the pole is at one side of the path of the sled runner.

The lower pointed end of the gee pole is connected to its eye bolt 45 by means of a hook member 49 that is mounted on the stem of the eye bolt 40 and the end 50 of which is adapted to enter a transverse opening with which the gee pole is provided.

As an added safety feature I propose to lash the gee pole to the hook 49 and to the eye bolt as shown at 51 in Fig. 1 and also to lash the gee pole to the eye bolt 44 as indicated at 52.

An advantage of this construction involving the pivotal connection of the bracket 37 to the sled is that the outer end of the gee pole may be swung up and down and thus placed in the most convenient position for the person who is operating the pole. This enables the operator to manipulate the pole while standing upright.

A sled embodying this construction is extremely sturdy and is capable of transporting heavy loads over rough surfaces.

It will be understood, of course, that the runners, bridge elements, slats, etc. will be made of wood which results in a sled of minimum weight. The manner of constructing the bridge element produces a sled which is extremely strong but which will, nevertheless, yield more or less when in use and will thus accommodate itself to any rough surface without danger of breaking.

The slats 26 are shown as being lashed to the bunks 11 by lacing or thongs 63, said bunks being provided with apertures 62 for this purpose.

The ends of the slats are shown as being lashed to the cross pieces 5 by suitable thongs or lacing 64.

I claim:

5. A sled comprising runners, a plurality of one-piece bridge elements connecting said runners and each formed of flat stock bent to present a horizontal central portion and a downwardly directed leg portion at each end, means connecting said leg portions to the runners, each bridge element having a slot formed in the upper end of each leg and the adjacent end of the horizontal portion, a bunk associated with each bridge element, each bunk having its central portion underlying the central portion of the bridge element and its end portions extending through the slots and engaging the lower ends thereof, each bunk having two shoulders on its upper side, one of which engages the inner end of one of the slots and the other of which is spaced from the inner end of the other slot, a key member inserted between said latter shoulder and the end of said slot thereby locking the bunk to the bridge element, a pole-supporting bracket pivotally connected to the front end of the sled and having at its forward end an eye bolt and a gee pole extending through said eye bolt and means securing the lower end of the pole to the side of the sled.

30. 2. A sled comprising runners, bridge elements connecting the runners, a cross bar connecting the runners at both the front and the rear of the sled, a gee pole bracket pivoted to the front cross bar and extending forwardly and laterally from the sled, the front end of said bracket being situated at one side of the path of travel of the sled, a gee pole, means connecting the gee pole to the forward end of the bracket, and other means connecting the lower end of the gee pole 40 to the side of the sled, said gee pole extending forwardly and outwardly.

45. 3. A sled comprising runners, bridge elements connecting the runners, a cross bar connecting the runners at the front of the sled, a gee pole bracket pivoted to the cross bar and extending forwardly and laterally therefrom, an eye bolt carried by the front end of the bracket, a gee pole extending through the eye bolt, a second eye bolt carried by the front bridge element and adapted to receive the lower end of the gee pole and means anchoring said lower end of the gee pole to said second eye bolt.

50. 4. A sled comprising runners, bridge elements connecting the runners, a cross bar connecting the runners at the front of the sled, a gee pole bracket pivoted to the cross bar and extending forwardly and laterally therefrom, an eye bolt carried by the front end of the bracket, a gee pole extending through the eye bolt, a second eye bolt carried by the front bridge element and adapted to receive the lower end of the gee pole, and an anchoring hook carried by the last-named eye bolt and adapted to engage in an aperture in the gee pole for anchoring the gee pole to said eye bolt.

VICTOR H. CZEKKA.
